UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

BUNCH-BUILDING MECHANISM FOR SPINNING FRAMES.

Application filed June 26, 1925. Serial No. 39,682.

To all whom it may concern:

Be it known that I, JONAS NORTHRUP, a citizen of the United States, residing at Hopedale, in the county Worcester and State of Massachusetts, have invented certain new and useful Improvements in Bunch-Building Mechanisms for Spinning Frames; and I do hereby declare the following to be a full, clear, and exact description of the invention, such as will enable others skilled in the art to which it appertains to make and use the same.

The present invention relates to an improvement in bunch building mechanisms for spinning frames.

In spinning filling for use on weft replenishing feeler looms, it is desirable to provide the bobbin with a small bunch near the butt of the bobbin, to be engaged by the feeler in order to secure the efficient operation of the weft replenishing mechanism of the loom. A need has therefore been felt for a bunch building attachment adapted to be applied to existing spinning frames, and particularly ring spinning frames of the Whitin type. To this end the invention consists in the bunch building mechanism hereinafter described and particularly defined in the claims.

In the accompanying drawings illustrating the preferred form of the invention, Figs. 1, 2, 3, 4, 5, 6 and 7 show successive positions of the bunch building mechanism in operation forming a bunch on the bobbin; Fig. 8 shows the traverse lever and associated parts for operating the ring frame to raise and lower it, with the bunch builder in the position which is assumed at or near the beginning of the bunch building operation; Fig. 9 is an enlarged view of part of the mechanism illustrated in Fig. 8; Fig. 10 is a front view of the bunch building mechanism; Figs. 11 and 12 illustrate, respectively, a plan and front view of the bunch builder arm tappet; Fig. 13 shows in plan parts of the bunch builder mechanism; Fig. 14 is a sectional elevation taken on the line 14—14, Fig. 9; Fig. 15 is a front elevation of a portion of the Whitin ring spinning frame, illustrating in general the ring traverse mechanism as provided with the bunch building mechanism of the present invention; and Fig. 16 illustrates six sectional elevations of the bobbin butt showing

the bunch in six successive forms, A, B, 55
C, D, E and F.

The illustrated embodiment of the invention is described as follows: Referring to Fig. 15, the spindle rail 1 carries the spindles upon which the bobbins 2 are placed, and the ring rail 3 is supported on the post 4. In the complete machine there are a number of such posts for supporting the ring rail, which are connected together and operate simultaneously. The ring rail posts 4 are connected by the bell crank lever 5, connected by means of a chain 6 with the chain stud 7 of the builder motion. The spinning frame is the Whitin ring frame.

The builder motion comprises the traverse lever 10, pivotally mounted at 11 upon a stationary part of the machine, provided with the counter-weight 12 in the usual manner. The traverse lever carries a cam roll 13, which is adapted to engage the traverse cam 14, mounted on the shaft 15, and rotated at a suitable rate of speed by gearing from the drive shaft of the spinning frame. The traverse cam is provided with surfaces, as shown, more especially in Figs. 1 and 8, which oscillate the traverse lever to depress it and to permit it to rise by means of the counter-weight on the lever 5 holding the roll 13 against the face of the cam. This imparts the oscillating movements to the traverse lever, which is connected by the chain 6 to the lever 5, which operates to raise and lower the ring rail 3. This traverse lever is provided with a slot 16, which receives the segmental rack 17. This rack is a segment of a worm wheel which is engaged by the worm 18 carried on the shaft 20, upon the front end of which is mounted the ratchet wheel 21. This ratchet wheel is turned by oscillations of the pawl lever 22, pivotally mounted on the shaft 20, carrying a spring pressed pawl 23, see Fig. 10. This pawl lever 22 is actuated by means of a rod 24, which is reciprocated in the usual manner. A holding pawl 25 is mounted on the bracket arm 26, and operates to engage the ratchet wheel 21 and hold it from backward movement. The front end of the worm shaft 20 is provided with a square hole to receive a crank for re-winding the mechanism to starting position, as will be hereinafter described.

The mechanism thus far described is a

mechanism of the Whitin ring frame, and is tappet 47, and swings the bunch builder familiar to those skilled in the art and needs no further description.

The bunch builder mechanism is mounted 6 on the traverse lever 10, and consists of mechanism for reciprocating the ring rail at the beginning of the operation of the frame to form four layers of yarn about one-half an inch long on the bobbin adjacent to 10 the butt thereof. This bunch building mechanism comprises a plate 30, which constitutes a frame for the mechanism. This plate 30 is bolted to the side of the traverse lever 10, in the position shown in Fig. 14. 15 It rests against the surfaces of the rack guide 31 and bearing support 32 of the traverse lever. A clamp plate 33 is applied to the opposite side of the traverse arm, as shown in Fig. 14, and a bolt 34, passing 20 through holes in the plates 32 and 33, secures the plate in place on the traverse lever. This plate 30 at its upper end carries a stud 35, upon which the bunch builder arm 36 is pivoted. A spring 37 normally tends 25 to move the bunch builder arm 36 to the left, as viewed in Fig. 1. A pawl arm 38, pivotally mounted at 40 on the lower end of the bunch builder arm 36, is provided on its 30 end with a pawl 41 which is a member adapted to engage the hook 42, secured to or formed integral with the tumbler 43. The pawl 41, at a certain point in the operation 35 of the bunch builder mechanism, turns the tumbler 43 from the position shown in Fig. 7 to that shown in Fig. 1. The tumbler 43 is triangular in shape, being pivoted at one corner on the stud 44, supported from the plate 30. This tumbler carries a roll 45 at a second corner, and is provided with a horn 46 at its third corner. The bunch builder 40 arm 36 is provided on its extreme lower end with a tappet 47. One end 48 of the tappet is secured by means of the bolt 50 to the bunch builder arm 36. The other end 51 of 45 the tappet extends into the path of motion of the rack 17. When the rack is in its extreme forward position, its end strikes the end 51 of the tappet 47, and swings the bunch builder arm 36 outwardly into the 50 position shown in Fig. 1. This position the bunch builder arm retains during the formation of the bunch on the bobbin.

The operation of the mechanism is as follows: After doffing the spinning frame, and 55 donning it with empty bobbins, the operative inserts his crank in the end of the shaft 20, throws the pawl 25 off of the ratchet wheel 21, and, holding the pawl 23 off of the ratchet wheel with his left hand, turns the 60 crank to the right, thereby turning the worm 18, and moving the segmental rack forward from the position shown in Fig. 9 to and beyond the position shown in Fig. 8. Just before the end of its forward movement, the rack 17 strikes the end 51 of the 65

arm 36 to the right, as viewed in Fig. 1, with the result that the parts assume the positions illustrated in that figure, the roll 45 and horn 46 of the tumbler 43 being ready 70 to engage the surface of the traverse cam 14, and to hold the traverse lever in the position shown in Fig. 1, as soon as the traverse lever 10 is permitted by the operative to rise, whereupon, through the connections 75 described, it supports the ring rail in proper position to begin the formation of the bunch. The pawl 25 is thrown on to the ratchet wheel 21, and the frame is started up. As the traverse cam 14 rotates in the direction of the arrow 52, Fig. 1, the tumbler 43 controls the position of the traverse lever, and the building of the bunch begins. During the first traverse of the ring rail it moves upwardly a sufficient distance to lay 80 upon the bobbin the yarn indicated in form A, Fig. 16. By this time the horn 46 will reach the depression 53 between two lobes of the traverse cam, as shown in Fig. 2, and continued motion of the traverse cam will 85 cause the tumbler to turn upon its stud 44 to the position shown in Fig. 3, at which time the ring rail will be depressed, and a second layer of yarn will be wound on the bobbin, as shown in form B, Fig. 16. As 90 the traverse cam continues its rotation, the tumbler 43 will move from the position shown in Fig. 3 to the position shown in Fig. 4, at which time the traverse lever cam roll 13 will engage the surface of the cam. During this movement of the parts from the position shown in Fig. 3 to the position shown in Fig. 4, a third layer of yarn will 95 be laid upon the bobbin, and the bobbin will assume the condition illustrated in form C, Fig. 16. Continued motion of the traverse cam 14 will now depress the traverse lever, only a part of a lobe of the cam 14 being employed for this purpose, and a fourth 100 layer of yarn will be laid on the bobbin, 105 which will then assume the condition illustrated in form D, Fig. 16. By this time the traverse cam and the other parts will have reached the position shown in Fig. 5, 110 and the tumbler 43 will have been turned to its new position. With continued operation 115 of the machine, the regular building of the bobbin will begin, the tumbler flopping over to the position shown in Fig. 6, very soon after passing the position shown in Fig. 5. As 120 the machine continues to operate, the cam 14 will permit the traverse lever 10 to rise, and the first layer laid on the bobbin by the regular operation of the traverse mechanism will be that shown on top of the bunch 125 in form E, Fig. 16. The second layer will bring the bobbin to the position shown in form F, Fig. 16, at which time the two layers of long traverse on the bobbin will 130 have been completed.

As the bobbin is now built up, the segmental rack 17 is withdrawn from behind the tappet 47, and the bunch builder arm is permitted to swing from the position shown in Fig. 6 to the position shown in Fig. 7. A considerable number of reciprocations of the transverse mechanism will be required to accomplish this withdrawal of the rack from behind the tappet, but the movement of the bunch builder arm inwardly will be inoperative to cause any movement of the tumbler or the associated parts of the bunch builder mechanism aside from the movement to the new position shown in Fig. 7. The bunch builder then retains the position of parts shown in Fig. 7 until the bobbins are completed, and then the operator stops the frame, puts his foot on the lever 5 and depresses the ring rail, doffs the bobbins and dons it with new ones. Then upon completion of winding back the rack, the tumbler is again swung into the position shown in Fig. 1, and the frame may be started up again as before. It is to be observed that the operation of re-setting the ring rail traverse mechanism automatically throws the bunch builder mechanism into operative position, and that the bunch builder mechanism then automatically performs its bunch building operation, at the end of which it automatically ceases such operation, and the normal formation of the bobbin continues thereafter. The mechanism requires no manipulation by the operator at any time.

The bunch builder mechanism operates to control the ring rail at the beginning of the operation of the frame to form four layers of yarn about one-half an inch long on the bobbin adjacent to the butt thereof, when the frame is started up with the parts in the position shown in Fig. 1. A useful feature of the invention resides in the fact that the operative may, if he desires to reduce the size of the bunch, start up the frame with the pawl in the position shown in Fig. 2, in which case there would be but three small layers of yarn on the bobbin, and this would make a much smaller bunch, which, in some instances, might be preferred.

One feature of advantage which arises from the present invention is the fact that after the bunch building operation is completed, the regular roll 13 of the traverse lever 10 takes control of the rail without any jar or jerk, the mechanism operating gradually to permit the traverse lever to rise until the roll 13 engages the traverse cam. In some bunch builders heretofore used, at the termination of the operation of the bunch builder, the traverse lever is permitted to move suddenly in order to bring the regular control into operation, and this has sometimes resulted in sudden motion of the ring

rail, which has sometimes caused the breaking of ends.

Having thus described the invention, what is claimed is:

1. Bunch building mechanism for spinning frames having means comprising a lobed traverse cam for controlling the traverse of the winding on the bobbin and means for varying the position of the traverse including a rack, having, in combination, a tumbler, means for supporting it in position to engage the traverse cam, and means for turning the tumbler from inoperative to operative position comprising a part adapted to be actuated by the rack, the movement of the rack in the direction to start the spinning of bobbins operating to turn the tumbler into engagement with the traverse cam.

2. Bunch building mechanism for spinning frames having means comprising a lobed traverse cam for controlling the traverse of the winding on the bobbin and means for varying the position of the traverse including a rack, having, in combination, a frame, a tumbler pivotally mounted on the frame, a hook secured to the tumbler, a pawl, and means for actuating the pawl from the rack to turn the tumbler into position in engagement with the traverse arm.

3. Bunch building mechanism for spinning frames having means comprising a lobed traverse cam for controlling the traverse of the winding on the bobbin and means for varying the position of the traverse including a rack, having, in combination, a frame adapted to be secured to the cop building motion, a swing lever having a portion attached thereto adapted to be engaged by the rack and provided with a pawl, a tumbler supported on the cop builder motion of triangular form provided with a hook, the pawl being adapted to engage the hook toward the end of the cop building operation, and to turn the tumbler cam when the rack is returned to starting position to bring two corners of the triangle into engagement with the surface of the traverse cam, the lobes of which act to turn the tumbler during two complete forward and back movements of the cop building motion a short distance sufficient to build a bunch near the butt of the bobbin, and thereafter to throw the tumbler into inoperative position for the reminder of the cop building operation.

4. Bunch building mechanism for spinning frames having means comprising a lobed traverse cam for controlling the traverse of the winding on the bobbin and means for varying the position of the traverse including a rack, having, in combination, a tumbler supported on the traverse cam of general triangular form pivoted at

one corner of the triangle, means for turning the tumbler into position with its two free corners in engagement with the lobes of the traverse cam, the tumbler co-operating with the surfaces of the traverse cam to cause the cop building motion to build a bunch on the bobbin near the butt, and to turn the tumbler through successive positions into an idle position, which it retains during the regular bobbin building operation of the frame.

5. Bunch building mechanism for spinning frames having means comprising a lobed traverse cam for controlling the traverse of the winding on the bobbin and means for varying the position of the traverse including a rack, having, in combination, a tumbler of irregular outline adapted to engage the traverse cam, means for moving the tumbler into operative position controlled by the rack, said tumbler being so shaped as to cause the cop building motion to build a bunch on the bobbin, and to throw the tumbler out of operation when the bunch is completed.

25. Bunch building mechanism for spinning frames having means comprising a lobed traverse cam for controlling the traverse of the winding on the bobbin and means for varying the position of the traverse including a rack, having, in combination,

tion, a tumbler of irregular outline adapted to engage the traverse cam, means for moving the tumbler into operative position controlled by the rack, said tumbler being so shaped as to cause the cop building motion to build a bunch on the bobbin and then to throw the tumbler out of operation without shock or jar when the bunch is completed. 35

7. Bunch building operation for spinning frames having means comprising a lobed traverse cam, a traverse lever having a part adapted to engage the traverse cam, the cam and lever normally controlling the traverse of the winding on the bobbin, and means for varying the position of the traverse including a rack having, in combination, an auxiliary traverse cam engaging device, and means for moving it into operative position controlled by the rack, said auxiliary traverse cam engaging device being so shaped as to cause the cop building motion to build a bunch on the bobbin and then to permit the gradual movement of the traverse lever into engagement with the traverse cam to restore it to control of the traverse of the 50 bobbin winding. 40

45 In testimony whereof I have signed my name to this specification.

JONAS NORTHROP.
